LEAD SEVERING CONTRIVANCE

William Widmaier, Lancaster, Pa., assignor, by mesne assignments, to the United States of America as represented by the United States Atomic Energy Commission

Application March 2, 1955, Serial No. 491,609

4 Claims. (Cl. 313—102)

This invention relates to severable lead-wire contrivances for use in inaccessible places such, for example, as the interior of an electron tube, and has special reference to the provision of improvements in the art of manufacturing electron tubes of the various kinds capable of utilizing such contrivances.

In the manufacture of electron tubes it is sometimes desirable to destroy the electrical continuity of one or more of its internal wires prior to operating the tube in its normal or intended manner. For example, it has previously been proposed (i) to evaporate photo-sensitive material onto an inner cathode surface of an evacuable envelope by means of an evaporator (e. g. a hot-wire) energized by current flowing through a conductor which is connected through a fuse to an electrode lead and (ii) to blow the fuse, subsequent to the evaporation process, by a surge of current applied through said lead. The trouble with this procedure is that the fuse-blowing surge, however brief, passes through the evaporator and releases an additional or surplus quantity of vaporizable material. This problem has long been recognized and the usual practice is to halt the evaporation process before the desired ultimate quantity of vaporizable material has been laid down and to rely upon the fuse-blowing surge to finish the job. This, obviously, involves a guess on the part of the operator as to the exact additional quantity of vaporizable material to be supplied by the fuse-blowing surge. As a consequence, the response characteristics of photo-sensitive electrodes made in this manner may vary from tube to tube.

Accordingly, the principal object of the present invention is to obviate the above described and other less apparent objections to present day severable lead-wire installations.

The foregoing and related objects are achieved in accordance with the invention (a) by applying a vaporizing current to the vaporizable material through a conductor having a heat-severable portion, (b) halting the application of the current when the desired ultimate quantity of vaporized material has been deposited upon the appropriate surface and (c) subsequently, in the absence of current, severing the heat-severable portion of said conductor. The conductor is severed by subjecting the severable portion thereof to heat transferred thereto from an auxiliary source such, for example, as a radio frequency oscillator. The severable portion of the conductor comprises a fuse which is immune to the vaporizing current that flows therethrough in its transit to the vaporizer. The fuse is preferably biased to open, to ensure a clean break. When an "activator," e. g. cesium, is used (to "sensitize" the photo-sensitive material) or when a "getter" is used (to clean up residual gases within the tube), pellets of said materials may be supported on the same structure as the fuse, whereby they are in a position to be evaporated by the same auxiliary source of heat that is used to blow the fuse.

The invention is described in greater detail in connec-

2

tion with the accompanying single sheet of drawings, wherein:

- Fig. 1 is an elevational view, partly in section, of the invention as applied to a photo-multiplier; the tube being "on the pump," and showing a photometer, for gauging the thickness of the photo-cathode layer, and an R. F. oscillator for blowing the fuse in the severable lead that carries the vaporizing current to the vaporizable material of which said layer is comprised;
- Fig. 2 is an enlarged view in perspective of the severable lead-wire contrivance used in the tube of Fig. 1; and Fig. 3 is a view, similar to Fig. 2, but showing a "getter" and cesium pellet as elements of the contrivance of the invention.
- In Fig. 1 the invention is shown as applied to photomultiplier tube 1 of more or less standard form and dimensions. The tube 1 is shown "on the pump" and is at that stage of its manufacture whereat a photo-emissive material (e. g. antimony) in the form of a pellet 3 is being evaporated by means of a hot-wire 5 onto the inner surface 7 of the front end or "window" to form the cathode 9 of the device. The hot-wire or "resistance element" 5 is strung between two supports 11 and 13, one of which is connected to the tube's disc-like accelerating electrode 15. The disc contains a central aperture (not shown) through which electrons normally pass in their transit to the first multiplying-electrode or "dynode" 17; hence the pellet 3 and the resistance element 5 upon which it is supported should be off-set from said aperture. As is conventional, the dynodes 17—22, which are here shown in an in-line array, are supported adjacent to their side edges on a pair of insulating strips 23 and 25 and are each provided with a lead 18a, etc. which extends to the exterior of the envelope. A metal film 27 on the inner side wall of the envelope, and a resilient wire 29 which is biased to bear against said film, provide an electrical connection between the photo-emissive cathode 9 and the cathode lead 9a.
- In evaporating the cathodic material 3, two of the electrode leads, in this case the lead 15a to the accelerating electrode 15 and the lead 18a to one of the dynodes, comprise the circuit for supplying the heating or vaporizing current to the evaporator 5 from an external source, exemplified by the battery 31. One of these leads, e. g. the lead 18a, contains the heat-severable contrivance of the invention.
- As shown in Figs. 1 and 2 the contrivance employed to break the electrical connection between the evaporator 5 and the external dynode-lead 18a, subsequent to the evaporation process, comprises three elements 33, 35, and 37, connected in series between the lead 18a (or the dynode 18, which it normally serves) and the evaporator 5. One of the three elements of the contrivance is a relatively infusible metal disc, loop or annulus 33 which is, by reason of its extended area, adapted to be heated quite rapidly by eddy currents induced therein from an external applicator such as the coil 39 in the output of a radio frequency oscillator 41.
- The second element of the combination comprises a fuse 35 constituted of a material which is immune to the heating current which passes therethrough during the evaporation process but which will melt or "blow" when subject to the much higher degree of heat to which it is subjected by reason of its direct contact with the heated loop or "secondary" 33 of the transformer 33 and 39. Aluminum is preferred as the fuse material because its vapor pressure (10^{-7} millimeters of mercury) at its melting point (660° C.) is lower than the air pressure (10^{-6}) employed in most vacuum tubes, and hence does not release any appreciable vapor within the tube when the fuse is blown. Alternatively, lead, bismuth or thallium,

or certain alloys thereof may be employed as the fuse material.

The third element of the contrivance comprises a bowed metal (e. g. tungsten) spring 37 which is connected at one end to the fuse strip 35 and firmly anchored at its other end, as by a weld to the insulated terminal 13 of the evaporator 5. The spring 37 is not essential to the practice of the invention but when used exerts its biasing force on the fuse 35 and hence ensures a rapid and clean break in the series connection between the evaporator 5 and its current source 31 when the fuse melts under the influence of heat supplied thereto through the loop or secondary 33 of the transformer 33, 39, by the oscillator 41.

When the vaporizable cathodic material 9 laid down on the foundation surface 7 by the evaporator 5 is of a type requiring the application of a film of sensitizing material, the cesium or other sensitizer may be supported on the same structure as the fuse, instead of being supported separately on the mica strip 25, as shown at 43, Fig. 1. Thus, as shown in Fig. 3 the sensitizing material for the cathodic layer 9 may be supported within a container 45 which may itself form the "secondary" by virtue of its flattened, round form. The container 45 is adapted to be heated by the same auxiliary source of heat (41, Fig. 1) that is used to blow the fuse 35. When the walls of the container 45 are heated the heat is conducted to the sensitizing material therein and vaporizes said material. The container 45 has apertures 46 through which the vaporized sensitizing material may pass to the cathode 9 through the evacuated interior of the tube. In order to insure that all of the sensitizing material is vaporized when the container is heated, cesium may be introduced into the tube by means of an exothermically reactive mixture which releases cesium on activation. For example, a mixture in the form of a powder may be used having a composition, by weight, of about 2 parts of cesium chromate to about 1 part of silicon. When the mixture is heated to its activation temperature cesium is released in vapor form.

The cesium sensitizing material may be vaporized after the fuse 35 is blown even though the sensitizing material has an activation temperature which is lower than the temperature at which the fuse blows. Induced radio frequency energy displays a phenomenon wherein the outer portions of a receiver of induced R. F. energy are heated more rapidly than the inner portions. Therefore, the outer surface of the container walls 45 are heated more rapidly than the sensitizing material within the walls. Since more of the energy picked up by the heating member is concentrated along the outer portions thereof as the frequency of the induced energy is increased, the use of a relatively high frequency, say about one megacycle per second, may be used to melt the fuse before the sensitizing material is evaporated.

The container 45 may also serve as a support for the "getter" used to clean up residual gas in the envelope 1 (Fig. 1). The getter material which is shown in Fig. 3 in the form of a short-wire 47, is attached, as by solder, directly to the container 45. Since the getter 47 is the last thing to be "flashed" its flash point should be higher than those of the fuse 35 and the sensitizing material in the container 45. A one-to-one mixture, by weight, of barium and aluminum provides a getter material of a satisfactorily high flashing temperature, in this case, 1150° C. Another example of a "high-temperature getter," in this case of the "chemical reaction" type, comprises about 100 parts of barium titanate to about 3.75 parts of beryllium. Its flashing temperature is about 1450° C.

Operation

When the switch 49 in the circuit that supplied heating current to the resistance element 5 is closed the cathodic

material 3 is heated and gradually vaporizes. The vaporized material condenses and forms a film or thin layer 9 upon the inner surface 7 of the tube window. The thickness and hence the response characteristic of this layer 9 may be gauged throughout its manufacture by a photometer device 51, including a phototube 53, actuated by light, from a lamp 55, passing through said layer. When the desired ultimate quantity of vaporized material has been deposited upon the window 7 the flow of current to the resistance element 5 is halted by opening the switch 49, either manually or automatically. Thereafter, in the absence of current in the resistance element 5, the fuse is blown by heat transferred thereto from the inductively heated disc or loop 33. Since there is no heating current flowing in the resistance element 5 at the time the fuse is being blown, the thickness and response-characteristics of the cathode layer are in no way affected by the fuse-blowing step. Hence the operator is relieved of all guess work.

While the invention has been described as applied to the manufacture of a phototube having a cathode of the photoemissive variety it is to be understood that the disclosure in this respect is illustrative, and that the invention is likewise applicable to other types of photoresponsive tubes having different varieties of photosensitive elements. For example, the invention may be applied to the manufacture of image-orthicons, vidicons and other varieties of "pick-up" tubes.

What is claimed is:

1. A severable lead-wire contrivance for use in an electron tube as a series connection between an electrode lead and a resistance element, said contrivance comprising a metallic element adapted to be heated by eddy currents induced therein from an external source, a fuse strip in said tube and connected at one end to said heater element and adapted to be blown solely by heat transferred thereto by conduction from said element, and a metal spring connected to the other end of said fuse strip and biased to open the same.
2. An electron tube comprising an envelope, a plurality of electrodes within said envelope, an electrical terminal connected to each of said electrodes within said envelope and extending through a wall of said envelope, an electrical circuit coupled between two of said electrodes and within said envelope, a vaporizable substance in heat transfer relation with a portion of said circuit, said circuit being adapted for heating said substance by means of electric current flow in said entire circuit, a fuse in said circuit and in said envelope and physically removed from said portion; and means other than said current flow for heating and blowing said fuse.
3. An evacuated envelope containing a surface to be sensitized, a resistance element mounted adjacent to said surface, a sensitizing material for said surface supported on said resistance element and adapted to be vaporized by heat generated as an incident to the flow of current through said element, a series circuit connected to said resistance element and extending to the exterior of said envelope, said series circuit comprising (1) a fuse mounted in said envelope and adapted to pass an electric current sufficient to subject said sensitizing material to its vaporizing temperature, and (2) an inductive element mounted in said envelope and in heat transfer relationship with respect to said fuse and adapted to be heated to a temperature sufficient to blow said fuse, in the absence of said heating current, by currents induced therein from an external source.
4. A severable electrical circuit within an envelope comprising an inductive element adapted to be heated by induction, a fusible member in physical contact with said inductive element and of a size capable of being fused only by induction, a resistance element in said circuit, a vaporizable material mounted on said resistance element, said resistance element being adapted to be heated to a

temperature sufficient to vaporize said material solely by current flow in said circuit.
